UNITED STATES PATENT OFFICE.

GIOVANNI BERTINETTI AND EDGARDO GATTINO, OF TURIN, ITALY.

DUPLICATING APPARATUS.

Application filed April 9, 1927, Serial No. 182,472, and in Italy December 29, 1926.

The present invention relates to duplication of writings, drawings, printed matter and the like by means of flexible printing plates consisting of very thin metal sheets, 5 say of aluminium, in which relief portions are provided by hand tracing or by pressure or by an impact action, as obtained say by means of the types of a standard typewriter.

10 The invention comprises a rotary duplicator in which a plate of the kind above referred to is fitted on a rotary drum in a direction transverse to it, that is with the writing lines arranged substantially along 15 parallel circles of the cylindrical surface of said drum and lying in planes perpendicular with respect to the drum axis.

The invention comprises also a rotary duplicator of the type above referred to, in 20 which are provided means for adjusting the pressure of the platen roller on the printing plate drum and for removing said pressure as soon as smooth portions of the printing plate are lying under the said platen 25 roller, as well as means for engaging said printing plate and tensioning it on said drum.

On the annexed drawings is shown by way of example a preferred embodiment of 30 the present invention, and:

Figure 1 is a side view of such embodiment;

Figure 2 is an end view looking toward the left in Fig. 1;

35 Figure 3 is a similar view looking toward the right in Fig. 1;

Figure 4 is a fragmentary horizontal section on an enlarged scale along broken line 4-4 of Fig. 6 of one longitudinal edge of 40 a segmental drum member carrying the printing plate, to show one of the clamping devices for said printing plate;

Figure 5 is a front view of the same edge and

45 Figure 6 is a cross-section to an enlarged scale of the printing plate carrier or segmental drum on line 6-6 of Fig. 1.

Referring to Figures 1, 2 and 3, 1 is the machine frame which is adapted to carry 50 a box 2 intended to contain supplies to be used with the machine; two standards 3 and 4 are fastened at the ends of said frame.

1 and constitute supports for the hollow rotary segmental drum 5 as hereinafter described.

55 Said drum is of substantially semi-cylindrical form and is provided at its ends with disk shaped heads 6-6' by means of which it is journaled on a stationary spindle 7 fastened on standards 3 and 4.

60 Said drum is rotated by any suitable means, say by means of a crank handle 8 actuating a pinion 9 mounted to rotate on standard 3 and meshing with a pinion 10 which is solid with head 6.

65 The printing plate, designated A in Figures 1 and 6, is located on the outer surface of the segmental drum 5 and the edges of said segmental drum are provided with means for clamping the printing plate edges 70 and for tensioning said printing plate.

70 Each of said clamping means consists of two bars 11^a and 12^a and 11-12 (Figures 4, 5, 6) interconnected at one end by a pivot pin 29 (Figs. 4 and 5) and having a stepped 75 cross section (Figure 6) so as to abut against each other along shoulders 11''-12''. On one edge of said segmental drum 5 the bar 11^a is fastened on the bar directly, and the adjacent drum edge is provided with an 80 overturned support 13 in which is mounted a plunger 30-acted on by a spring 14 which bears on the cooperating bar 12^a when the latter is engaged with the bar 11^a to force the bars against each other and grasp therebetween the edge of the printing plate (see left portion of Fig. 6).

85 On the opposite edge of segmental drum 5 (right hand portion of Fig. 6) the bar 11 is pivoted on aligned pivot pins 11' in 90 heads 6-6' (Fig. 5) and thus the said bar may be swung around the axis of pins 11' which is distinct from the bar axis; said bar 11 has a fork 15 adapted to embrace a screw threaded spindle 16 which is fastened 95 on a projection 32 of drum 5 and has at its end a nut 17 adapted to compress a spring 43 located on said spindle between said nut and fork 15. Angular lugs 31 fastened on bar 11 act to engage bar 12 and hold it in 100 position over bar 11 with the printing plate edge engaged therebetween. Cups 44-44 loose on spindle 16 improve the manipulation of the parts.

The printing plate edges are engaged between bars 11^a—12^a and 11—12 respectively by moving bars 12—12^a around the respective pivot pins 29 as shown by the arrow in Fig. 4, and then said bars 12^a—12 are swung back over cooperating bars 11^a, 11 to grasp said printing plate edges between the shoulders or abutments of said bars.

Then by manipulating nut 17 the bars 10 11—12 may be moved inwardly (Fig. 6) as a unit to tension the printing plate A located over the segmental drum 5 and having its edges engaged between bars 11^a—12^a and 11—12 respectively.

15 On standards 3 and 4 is also mounted a spindle 33 journalled in bearing blocks 18 which are slideable in said standards and are acted on by springs 19 and by arms 20 engaging the ends of said spindle 33, thus 20 enabling the operator to move said bearing blocks 18 and spindle 33, with the platen roller 21 on said spindle, away from the spindle 7 and drum 5 against the action of said springs 19. The arms or levers 20 are 25 provided with pairs of notches 45 in their upper surfaces, as shown in Figs. 2 and 3; and these notches, in turn, coact with pins 46 fixed to standards 3 and 4, whereby said arms are retained in either normal or operated 30 position. The platen roller 21 has a lining of soft material, adapted to produce the required printing pressure on the paper to be printed on, to force it on the printing plate A during the printing operation.

35 The pressure of platen roller 21 against segmental drum 5 and printing plate A must be removed at given periods in the revolution of the segmental drum 5 in order to make the platen roller pressure ineffective 40 when in register with portions of said printing plate which are free from printing reliefs, so as to prevent the paper from being forced against the printing plate or against the inking surfaces in the portions where no 45 printing is to occur.

For this purpose the heads 6—6' project slightly above the surface of the drum 5 on which the printing plate is located, as shown in Figure 1.

50 More particularly, the amount of projection of heads 6—6' over the surface of said drum 5 is less than the combined thickness of the relief portions of the printing plate and of the inking means, if any, and greater 55 than the combined thickness of the smooth portions of the printing plate and the inking means, if any, if such inking means are located intermediate the printing plate and the paper to be printed on, as in the present 60 construction.

Thus it follows that the reliefs of the printing plate may exert a printing pressure on the paper, while the smooth portions of the printing plate and of the inking means, 65 if any, are prevented from contacting with

and soiling the paper, the platen roller 21 being held spaced therefrom by the projecting edges of heads 6—6'.

Of course in this connection the thickness of the paper is of no material account; however, if required, due account of the thickness of the material to be printed on may be had in proportioning the projection of heads 6—6' over the surface of segmental drum 5.

For the same purpose collars may be provided on the ends of the platen roller 21, said collars bearing on the surface of heads 6—6' to hold the surfaces of platen roller 21 and segmental drum 5 spaced from each other to the required extent.

To provide for a larger spacing of the platen roller and the drum in register with the edges of the printing plate where the paper to be printed must be prevented from being soiled, said heads 6—6' are each provided with spacers 22 covering a portion of the periphery of the same and adjustable on spindle 7 by means of wings 23 whose angular position on heads 6—6' may be adjusted at will by means of slots 24 and set 85 screws 25. Each of said spacers 22 provides thus for increasing the size of the cooperating heads 6—6' at the required point and for separating the platen roller 21 from the printing surface.

95 In the apparatus as above described the printing is effected by means of an inking ribbon 26 located on bobbins 27 and 28 mounted to rotate in said drum 5, said bobbins being operated during each revolution 100 of drum 5 to move the said ribbon one step forward.

This operation is obtained by means of ratchet pinions 34—35 rigidly attached to bobbins 27 and 28 and actuated by a pawl 36 pivoted for swinging movement on a pin 41 fixed to a slide 37 which is mounted to reciprocate in guides 38 provided on head 6, said slide having a pin 39 adapted to strike against a stationary abutment 40 on the 110 inner face of standard 4 during each revolution of the drum 5 and head 6 carrying it; a spring 42 acts to force the pawl 36 into engagement with either of ratchet pinions 34—35 at will, as apparent.

115 For the removal of the inking ribbon 26 the bobbins 27—28 have their ends journalled in heads 6—6' by means of spring pressed pins (not shown) adapted to be pushed back by a longitudinal movement of the bobbins, to permit the disengagement of the latter from said heads 6—6'.

The printing plate could also be inked by other means, say by an inking roller, in the well known manner.

125 The operation is as follows: The printing plate which consists, as stated above, of a thin metal sheet A having writings in relief thereon obtained by inserting the sheet in a typewriter in lieu of a paper sheet and 130

manipulating the keys in the usual manner, is located on the surface of the segmental drum 5 (Fig. 6) with the lines of writing arranged in transverse direction with respect to the axis of said drum and its lower edge is engaged between bars 11^a—12^a which are then clamped on each other to grasp said edge therebetween; said printing plate is carefully arranged over the surface of drum 5 and its upper edge is then engaged between bars 11—12 whereafter the knob 17 is manipulated to cause the interconnected bars 11—12 to move around the pivot pins 11' and to tension said printing plate. 15 The spacers 22 are then moved into register with the edges where the printing plate is not provided with writings and are fastened in adjusted position by means of the set screws 25 and then the ribbon bobbins 27—28 20 are located in position in the heads 6—6' with the ribbon 26 arranged over the printing plate.

A paper sheet is then inserted between the platen roller 21 and the segmental drum 5 having the printing plate and the ribbon thereon, and the handle 8 is rotated; said sheet is thus engaged between said platen roller 21 and drum 5 and moved forward therebetween, it being at the same time forced by springs 19 and platen roller 21 30 against the inking ribbon and printing plate so that the writings of said printing plate are thus reproduced on said sheet.

The printing pressure is produced by 35 springs 19 acting on spindle 33 of platen roller 21, and said pressure is operative only in respect of these reliefs of said printing plate which project beyond the rims of heads 6—6'; while in register with depressed or 40 smooth portions of said printing plate or of edges of the same, the pressure action is removed by the projecting ends of heads 6—6' or by the spacers 22.

Owing to the described arrangement of 45 the printing plate, the printing operation begins at one side of the writing and goes forward along the writing lines which provide a set of parallel and substantially even spaced ribs located along peripheral lines 50 of said printing plate and segmental drum, so that the inking ribbon is prevented from projecting into the spaces intermediate the writing lines as could happen should the printing operation proceed in a direction 55 perpendicular to the writing lines.

Very satisfactory and clean prints may thus be produced from printing plates consisting of very thin metal sheets having embossed printing reliefs or characters.

As apparent from the above description of 60 the operation, the method according to the present invention involves the arrangement of a printing plate consisting of a thin metal sheet having reliefs providing lines of writing or other matters to be duplicated, on

a support having the shape of a portion of a cylinder, with the lines of writing arranged along parallel circles lying on said cylindrical surface; and, further, the present invention involves the use of spacing 70 means cooperating with a platen roller, said means being adapted to move said platen roller away from said printing plate support and the inking means located thereon, if any, to such an extent as to prevent contact of the material to be printed on with the reliefs of said printing plate and inking means. 75

By the above method of printing a plate of the described character, the result is 80 obtained that the pressure is evenly distributed over the whole extent of the line of contact between said printing plate and platen roller, the writing being distributed in a substantially even manner over the 85 whole extent of the printing plate; and the relief lines of the printing plate provide annular ribs which act to hold uniform and even the distance and pressure of the printing plate drum and platen roller with respect to each other. 90

Further, owing to said arrangement, the inking ribbon located between said printing plate and platen roller is held stretched without being liable to become wrinkled 95 and to enter the spaces between the writing lines as it would do should parallel relief lines and depressions come in register with the platen roller as in the case of a printing plate arranged with relief lines of writings 100 parallel with the contact line of the printing plate and platen roller.

What we claim as our invention and desire to secure by United States Letters Patent is:—

1. A duplicating apparatus for printing from a printing plate that consists of a metal sheet having relief printing characters thereon, comprising support parts, a drum mounted to rotate on said support parts, means for driving said drum, means for clamping a sheet metal printing plate on said drum with its lines of writing transverse to the axis of said drum, a platen roller, means for forcing said platen roller 110 against said printing plate and drum, means for inking said printing plate, and means for removing the printing pressure from the flat portions of said plate. 115

2. A duplicating apparatus for printing 120 from a printing plate that consists of a metal sheet having relief printing characters thereon, comprising support parts, a segmental drum mounted to rotate on said support parts, means for driving said drum, means on one of the edges of said segmental drum to grasp one edge of said printing plate, said printing plate being arranged on said drum with its lines of writing transverse to the axis of said drum, means on the 125 130

other edge of said segmental drum for grasping the other edge of said printing plate and for tensioning said printing plate, a platen roller, means for forcing said platen 5 roller against said printing plate and drum, means for inking said printing plate and means for removing the printing pressure from the flat portions of said printing plate.

3. A duplicating apparatus for printing 10 from a printing plate that consists of a metal sheet having relief printing characters thereon, comprising support parts, a segmental drum mounted to rotate on said support parts, means for driving said drum, 15 means on one of the edges of said segmental drum to grasp one edge of said printing plate, said printing plate being arranged on said drum with its lines of writing transverse to the axis of said drum, means on the 20 other edge of said segmental drum for grasping the other edge of said printing plate, said grasping means consisting each of longitudinally stepped bars adapted to be clamped on each other with an edge of 25 said printing plate therebetween, means acting on one of said grasping means for tensioning said printing plate on said drum, a platen roller, means for forcing said platen roller against said printing plate and drum, 30 means for removing the printing pressure from the flat portions of said plate, and means for inking said printing plate.

4. A duplicating apparatus for printing 35 from a printing plate that consists of a metal sheet having relief printing characters thereon, comprising support parts, a segmental drum mounted to rotate on said support parts, means for driving said drum, means on one of the edges of said segmental 40 drum to grasp one edge of said printing plate, said printing plate being arranged on said drum with its lines of writing transverse to the axis of said drum, means on the other edge of said segmental drum for grasping 45 the other edge of said printing plate, said grasping means consisting each of a longitudinally stepped bar and of a respectively-movable and counter-stepped bar, co-operating means on said bars for clamping them on each other with one edge of said 50 printing plate therebetween, means acting on one of said grasping means for tensioning said printing plate on said drum, a platen roller, means for forcing said platen roller 55 against said printing plate and drum, means for inking said printing plate, and means for removing the printing pressure from the flat portions of said printing plate.

5. A duplicating apparatus for printing 60 from a printing plate that consists of a metal sheet having relief printing characters thereon, comprising support parts, a segmental drum mounted to rotate on said support parts, means for driving said drum, 65 means on one of the longitudinal edges of

said segmental drum for grasping one edge of said printing plate, said printing plate being arranged on said drum with its lines of writing transverse to the axis of said drum, means on the other longitudinal edge 70 of said segmental drum for grasping the other edge of said printing plate, means for shifting the grasping means for the last-named printing plate edge with respect to the first-named one for tensioning said printing plate on said drum, a platen roller, means for forcing said platen roller against said printing plate and drum, means for inking said printing plate, and means for removing the printing pressure from the 75 flat portions of said printing plate.

6. A duplicating apparatus for printing 80 from a printing plate that consists of a metal sheet having relief printing characters thereon, comprising support parts, a segmental drum mounted to rotate on said support parts, means for driving said drum, means on one of the longitudinal edges of 85 said segmental drum for grasping one edge of said printing plate, said printing plate being arranged on said drum with its lines of writing transverse to the axis of said drum, means on the other longitudinal edge 90 of said segmental drum for grasping the other edge of said printing plate, the last-named means being pivoted on said segmental drum along a line distinct from the line of grasping of said printing plate edge 95 therebetween, means for adjusting said last-named grasping means with respect to said pivotal line for tensioning said printing plate on said drum, a platen roller, means for forcing said platen roller against said printing plate and drum, means for inking 100 said printing plate, and means for removing the printing pressure from the flat portions 105 of said plate.

7. A duplicating apparatus for printing 110 from a printing plate that consists of a metal sheet having relief printing characters thereon, comprising support parts, a segmental drum mounted to rotate on said support parts, means for driving said drum, means on the edges of said segmental drum for 115 grasping and tensioning said printing plate on said drum, said printing plate being arranged on said drum with its lines of writing transverse to the axis of said drum, an inking ribbon passing over said printing plate and segmental drum, means in said segmental drum for supporting and feeding said inking ribbon, a platen roller, means for forcing said platen roller against said inking ribbon, printing plate and drum, and means for removing the printing pressure 120 from the flat portions of said printing plate.

8. A duplicating apparatus for printing 125 from a printing plate that consists of a metal sheet plate having relief printing characters thereon, comprising support parts, a seg- 130

- mental drum mounted to rotate on said support parts, means for driving said drum, means on the edges of said segmental drum for grasping and tensioning said printing 5 plate on said drum, said printing plate being arranged on said drum with its lines of writing transverse to the axis of said drum, an inking ribbon passing over said printing plate and drum, removable bobbins in said 10 drum for supporting said inking ribbon, means on said drum and supporting parts to drive either of said bobbins one step during each revolution of said drum, a platen roller, means for forcing said platen roller against 15 said inking ribbon, printing plate and drum, and means for removing the printing pressure from the flat portions of said printing plate.
9. A duplicating apparatus for printing 20 from a printing plate that consists of a metal sheet having relief printing characters thereon, comprising support parts, a drum mounted to rotate on said support parts, means for driving said drum, means for clamping a 25 sheet metal printing plate on said drum with its lines of writing transverse to the axis of said drum, a platen roller, means for forcing said platen roller against said printing plate and drum, means for inking said 30 printing plate, and spacing means between said drum and platen roller, said spacing means having a thickness greater than that of the flat portions of said printing plate but less than the combined thickness of the 35 printing plate and its relief portions and the sheet to be printed.
10. A duplicating apparatus for printing 40 from a printing plate that consists of a metal sheet having relief printing characters thereon, comprising support parts, a drum mounted to rotate on said support parts, means for driving said drum, means for clamping a 45 sheet metal printing plate on said drum with its lines of writing transverse to the axis of said drum, a platen roller, means for forcing said platen roller against said printing plate and drum, means for inking said printing plate, and projecting portions at the heads of 50 said drum and engaging said platen roller, said portions projecting to an extent greater than the thickness of the flat portions of said plate but less than the combined thickness of the printing plate and its relief portions and the sheet to be printed, and spacing means between said platen roller and said drum, said spacing means being angularly adjustable on said drum.
11. A duplicating apparatus for printing 55 from a printing plate that consists of a metal sheet having relief printing characters thereon, comprising support parts, a drum mounted to rotate on said support parts, means for 60 driving said drum, means for clamping a sheet metal printing plate on said drum with its lines of writing transverse to the axis of said drum, a platen roller, means for forcing said platen roller against said printing 65 plate and drum, means for inking said print-
- ing plate, and adjustable spacing means between said platen roller and drum.
12. A duplicating apparatus for printing 70 from a printing plate that consists of a metal sheet having relief printing characters thereon, comprising support parts, a drum mounted to rotate on said support parts, means for driving said drum, means for clamping a sheet metal printing plate on said drum with its lines of writing transverse to the axis of 75 said drum, a platen roller, means for forcing said platen roller against said printing plate and drum, means for inking said printing plate, spacing members between said plate drum and platen roller, said spacing 80 members being adjustable angularly on said drum, and means for fastening said spacing members in adjusted position.
13. A duplicating apparatus for printing 85 from a printing plate that consists of a metal sheet having relief printing characters thereon, comprising support parts, a drum mounted to rotate on said support parts, means for driving said drum, means for clamping a sheet metal printing plate on said drum with 90 its lines of writing transverse to the axis of said drum, a platen roller, means for forcing said platen roller against said printing plate and drum, means for inking said printing plate, projecting portions at the heads of 95 said drum and engaging said platen roller, said portions projecting to an extent greater than the thickness of the flat portions of said plate but less than the combined thickness of the printing plate and its relief portions and the sheet to be printed, and spacing means 100 between said platen roller and said drum, said spacing means being angularly adjustable on said drum.
14. A duplicating apparatus for printing 105 from a printing plate that consists of a metal sheet having relief printing characters thereon, comprising support parts, a drum mounted to rotate on said support parts, means for driving said drum, means for clamping a sheet metal printing plate on 110 said drum with its lines of writing transverse to the axis of said drum, a platen roller, means for forcing said platen roller against said printing plate and drum, means for inking said printing plate, and means for maintaining the active surfaces of said 115 drum and platen roller at a distance apart less than the combined thickness of the printing plate and the sheet to be printed. 120
15. A duplicating apparatus for printing 125 from a printing plate that consists of a metal sheet having relief printing characters thereon, comprising a supporting member for said printing plate, a platen member, an inking ribbon arranged between said printing plate and platen member, means for supporting and feeding said inking ribbon, means for pressing said supporting member and platen member against each other, with 130

- the inking ribbon and a work sheet to be printed between them, means for producing a displacement of the surface of the printing plate with relation to the platen member
- 5 in the direction of the lines of writing of said printing plate, and means for maintaining the active surfaces of said supporting member and platen member at a distance apart greater than the combined thickness
- 10 of the flat portions of said printing plate and the inking ribbon, but less than the combined thickness of the printing plate and its relief portions, the inking ribbon and the work sheet.
- 15 16. A duplicating apparatus for printing from a printing plate that consists of a metal sheet having relief printing characters thereon, comprising a supporting member for said printing plate, a platen member, an inking ribbon arranged between said printing plate and platen member, means for supporting and feeding said inking ribbon, means for displacing and pressing the surface of the printing plate with relation
- 20 to the platen member, and means for maintaining the active surfaces of said supporting member and platen member at a distance apart greater than the combined thickness
- 25 of the flat portions of said printing plate and the inking ribbon, but less than the combined thickness of the printing plate and its relief portions, the inking ribbon and the work sheet.
17. A duplicating apparatus for printing from a printing plate that consists of a metal sheet having relief printing characters thereon, comprising supporting parts, a drum mounted to rotate on said supporting parts, means for clamping a sheet metal printing plate on said drum, a platen roller, an inking ribbon arranged between said printing plate and platen roller, means for supporting and feeding said inking ribbon, means for forcing said drum and platen roller against each other with said printing plate, inking ribbon and a work sheet to be printed therebetween, and means for maintaining the active surfaces of said drum and platen roller at a distance apart greater than the combined thickness of the flat portions of said printing plate and the inking ribbon, but less than the combined thickness of the printing plate and its relief portions, the inking ribbon and the work sheet.
- In testimony whereof we affix our signatures.
